UNITED STATES PATENT OFFICE.

CLARENCE W. HAHN, OF NEW YORK, N. Y.

INK-RECEPTACLE.

1,286,603.

Specification of Letters Patent. Patented Dec. 3, 1918.

Application filed April 13, 1916. Serial No. 90,819.

To all whom it may concern:

Be it known that I, CLARENCE W. HAHN, a citizen of the United States, residing at New York, in the county of New York and 5 State of New York, have invented certain new and useful Improvements in Ink-Receptacles, of which the following is a full, clear, and exact description, such as will enable others skilled in the art to which it apper- 10 tains to make and use the same.

This invention relates to ink receptacles, and more particularly to such devices for installation in schools and other institutions where ink is provided for general use.

15 The primary object of the invention is to provide simple, practical and inexpensive devices whereby the ink wells may be securely locked against removal and which are adapted for general application to pre- 20 existing installations.

Another object is to provide devices of the character mentioned wherein the wells may be readily removed when desired, and wherein the same are normally incased to 25 be substantially air-tight and dust-proof.

Other objects will be in part obvious and in part noted hereinafter in connection with the following description of a typical embodiment of the invention illustrated in the 30 accompanying drawings, wherein—

Figure 1 is a plan view of my improved receptacle;

Fig. 2 is a sectional view on the longitudinal center line of Fig. 1;

35 Fig. 3 is a plan view of one of the parts; and

Fig. 4 is an end view of the cover.

As shown, the invention is embodied in a receptacle designed for installation in the 40 desks of public schools, having a support 1 typical of a pen rack or desk top, provided with a circular bored opening 2 commonly employed to receive an ink well.

In order to adapt my device for pre-existing supports having openings of different 45 diameter, and for other purposes to be described, there is provided a flat metal supporting plate 3 of the conformation shown in Fig. 3 designed for permanent attachment 50 to the support 1. This plate 3 is preferably punched from flat stock to provide a central well opening 4 having a notched wall downturned and provided with lateral projections 5 constituting a ledge to receive the

flange of a well cup 6. The plate 3, at one 55 end (the left of Fig. 3), is provided with a slot 7 disposed above a recess 8 cut in the support 1. An ink well 9 of glass or other suitable material is disposed within the cup 6 and preferably provided with a flat upper 60 edge, on which may be seated an annular washer 10 of rubber or other compressible material.

A cover plate 11 of flat stock and having a plan configuration substantially identical 65 with the plate 3 is provided as a cover for the receptacle to prevent removal of the well 9. The cover 11 has a central opening 12 in registry with but smaller than the well opening in the plate 3, so that when the 70 cover is positioned, access may be had to the ink, although the well 9 is locked against removal. The plate 11, at one end (the left of Fig. 2), has a down and inturned lug 13 75 extending parallel to the lower plate 3 and of a length to pass through the slot 7 when the cover is applied vertically. After such placement the cover 11 is adapted for sliding movement toward the right of Fig. 2 to bring the latching lug 13 beneath the edge 80 of the plate 3 adjacent the slot 7 whereby these parts are locked together. At the opposite end the cover plate has a forked extremity 14, the material of the plate between the tines being bent downwardly and then 85 at right angles parallel with the upper surface into a locking extension 15 having a relatively narrow recess 16 extending longitudinally. A tubular metal key guide 17 is permanently and rigidly secured to the 90 cover plate 11, as for example by transverse cuts 18 in opposite walls, within which are snugly received the tines of extension 14.

The support 1 is cut away to provide a 95 recess 19, which may conveniently communicate with the well opening 2. A screw bolt 20 having a round head and square shank is driven upwardly through the support to extend a short distance in the recess 19. This bolt is permanently carried by the support. 100 In mounting the receptacle the plate 3 is first secured to the support by a screw 21 with the well cup 6 and well 9 in position. Thereafter the cover plate 11 is vertically positioned to carry its bent latch extremity 105 13 through the slot 7, and the down-turned end 15 with associated parts into the recess 19 at the other side of the well. Thereupon

the cover plate is moved to the right (Fig. 2) to lock with the left extremity of the supporting plate 3 and project the two tines of the downturned locking extension 15 at the other end of the cover on opposite sides of the projecting end of the screw bolt 20. A hexagonal nut 22 is then fitted in the key guide 17 and screwed upon the bolt 20 to prevent movement of the cover plate either upwardly or toward the left. For convenience there may be employed a key 23, as shown in Fig. 2, to effect locking and unlocking of the receptacle. This key, known in the trade as a banjo key, is provided with a slightly tapering hexagonal recess so that the nut 22 may be pressed frictionally therein, whereby insertion and centering of the nut in the guide is expedited.

A cover member 24 is provided to close the opening 12 in the plate 11. This member is preferably hinged at one end by a depending lug 25 overturned beneath the plate 11, so that the cover is free to swing in the plane of the plate. In order to prevent distortion of the cover 24 there may be further provided a curved retention member 26 riveted to the cover plate 11, as shown in Fig. 1. The supporting plate 3 is also provided with a small opening 27 to accommodate the overturned end of the pivot lug 25, so that the cover plate and supporting plate will fit snugly together.

The plates 3 and 11 are preferably of a stiff metal of a thickness to prevent separation by insertion therebetween of an instrument such as a knife blade. The tubular key guide 17 is also of a diameter to permit snug insertion of the key 23, but to prevent rotation of the locking nut 22 by means other than the key properly designed therefor. The guide 17 also serves to prevent access to the locking means by mutilation of the support 1 adjacent thereto.

A particular advantage of the embodiment of the invention illustrated in the drawings resides in the capability of its manufacture from stock materials and accordingly at a minimum expense. While this feature is of material importance in the device for general application where relative cheapness is essential, it will be understood that various changes and modifications may be made in the construction of the various parts without departure from the intended scope of the invention or the appended claims.

Having described my invention, what I

claim as new and desire to secure by Letters Patent is:—

1. In a device of the character described, in combination, a support having a well opening and an adjacent recess, a cover plate removably secured to said support and having a downturned extension disposed in said recess, locking means for said extension associated with said support, and a metal tubular key guide in said recess above said means.

2. In a device of the character described, in combination, a supporting plate having a well opening with downturned flanges thereabout affording a ledge, a well cup supported on said ledge, a well in said cup, a compressible washer on the upper edge of said well, a cover plate to slidably interlock with said supporting plate at one point and compress said washer, and locking means to secure said cover plate against removal.

3. In a device of the character described, in combination, a supporting plate having a well opening and an adjacent recess, a cover plate having an opening in registry with but smaller than said first-mentioned opening, said cover plate being adapted for vertical placement on said supporting plate and for interlocking therewith by sliding thereon and having a downturned extension disposed in said recess, locking means for said extension, and a tubular key guide above said means.

4. In a device of the character described, in combination, a flat metal well support, a flat metal cover plate having sliding engagement therewith and having a part to interlock with said support during such sliding, and countersunk locking means to secure said plate against reverse sliding.

5. In a device of the character described, in combination, a well support, a cover therefor movable horizontally to engage therewith, countersunk locking means including a member movable relatively to said cover to secure the latter against horizontal disengaging movement, and means including a metal key guide encircling said member adapted to prevent lateral access to the latter.

In testimony whereof I affix my signature, in the presence of two witnesses.

CLARENCE W. HAHN.
